T. M. WILKINS.
SYSTEM FOR REGULATING MECHANICAL STOKERS FOR STEAM GENERATORS.
APPLICATION FILED APR. 16, 1919.

1,395,377.

Patented Nov. 1, 1921.

UNITED STATES PATENT OFFICE.

THOMAS M. WILKINS, OF EAST RANDOLPH, NEW YORK, ASSIGNOR OF ONE-HALF TO
JOHN W. STORKE, OF ERIE, PENNSYLVANIA.

SYSTEM FOR REGULATING MECHANICAL STOKERS FOR STEAM-GENERATORS.

1,395,377.

Specification of Letters Patent.

Patented Nov. 1, 1921.

Application filed April 16, 1919. Serial No. 290,631.

To all whom it may concern:

Be it known that I, THOMAS M. WILKINS, a citizen of the United States, residing at East Randolph, in the county of Cattaraugus and State of New York, have invented certain new and useful Improvements in Systems for Regulating Mechanical Stokers for Steam-Generators; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to a system for regulating mechanical stokers for steam generators, and consists substantially in so combining a plurality of pressure controlled valves that the supply of fuel to the furnace fire of a steam generator is automatically controlled, and the supply of steam generated effectually regulated.

The features of my invention are herein-after described and pointed out and are illustrated in the accompanying drawings, in which:—

Figure 1, is a diagrammatic drawing illustrating my invention.

Fig. 2, is a side elevation of a detail of the same.

Fig. 3, is a longitudinal section of the same, on the line 2 in Fig. 2.

Fig. 4, is a transverse central section of the same.

Fig. 5, is a view in elevation of one of the valves, partially in section, of my invention.

In these drawings A indicates a steam supply pipe leading from a steam generator (not shown) to a steam engine, or other point of use (not shown). Suitably connected with the supply pipe A are steam conducting pipes A', A² and A³, as may be desired. The conductor pipe A' leading to a pressure controlled valve B, conductor pipe A² leading to a pressure controlled valve B', and the pipe A³, to a pressure controlled valve B², said valves are each provided with mechanisms C, C' and C² adapted to actuate said valves as herein-after described; which valves and mechanism are shown and described in U. S. Letters-Patent No. 1,199,847 issued to me October 3, 1916, and U. S. Letters-Patent No. 1,294,586, issued to me

February 18, 1919, so that detailed description of the construction and operation thereof is not necessary.

Connected to the lower end of the conductor pipe A' is a reducing nipple a, having a longitudinal opening a'—a² therethrough the portion at a' being reduced, as shown in Fig. 3, so that but a small volume of steam will flow therethrough with relation to the volume which can flow through the valve B when the same is opened. This nipple a is also provided with a lateral opening in which a pipe D is secured, as shown on Fig. 4. The nipple a is secured in the intake side of the valve B, and from said valve a pipe E leads to the atmosphere.

From the conductor A' or other suitable point, a conductor F leads to the pressure controlled mechanism C which actuates the valve B so that a decrease of pressure in the steam main A is communicated through the pipe F to the pressure controlled mechanism C of the valve B, thereby causing said valve to open and permit the compressed steam in the nipple a and connected pipe D, to escape to the atmosphere.

The pipe D leads to the pressure controlled mechanism C' of the valve B', which has its intake side communicating with the steam main through a conductor pipe A². From the other side of the valve B' a conductor leads to a valve E² controlled by a governor mechanism e of ordinary construction, and thence to a fan engine or other motor (not shown) the speed of which motor is controlled by the action of said governor e. Preferably I connect a branch pipe e' with the pipe F between the valve B' or B² as the case may be, and the valve E², and lead the same to a cylinder and piston mechanism G for operating a damper G' in the smoke flue G² of the boiler furnace (not shown) so that when the pressure in the pipe D decreases, the mechanism C' opens the valve F and steam flows therethrough to the fan engine, and simultaneously actuates the cylinder and piston mechanism to open the damper G', as shown by broken lines, and in like manner a decrease of pressure in the pipe D permits the pressure controlled mechanism C² to open the valve B², thus permitting steam to flow therethrough to the governor mechanism e' of a stoker engine, so that simultaneously with the opening of the

damper G and speeding up of the fan engine (not shown) the movement of the stoker mechanism will be accelerated, which acceleration will continue until the pressure in the steam main A and conductor A' operates the pressure controlled mechanism C to close the valve B so that steam which flows through the restricted opening a' instead of escaping through said valve, will flow through said restricted opening until the pressure in the pipe D, is sufficient to operate the pressure controlled mechanism C' and C² to close the valves B' and B².

The valves B, B' and B² are identical in construction and operation, with the exception that the valves B' and B² are provided with restricted openings H, (see Fig. 5) which permits a minimum of steam to flow therethrough sufficient in volume to keep the engines, connected therewith, turning over. The valve B is not provided with such an opening. The number of regulating valves B' and B² connected with the pipe D may be increased, if desired, as the valve B may be used as a master valve for an indefinite number of stoker engines; as the greater the number of stoker engines used, the lower will be the percentage of steam wasted through the pipe E for each stoker. This system permits of an instantaneous unloading of the pressure holding the valves B' and B² closed by reason of a small reduction of pressure in the steam main A, thereby causing a quick acceleration of the engines connected with said valves, while the time required to build up the pressure in the pipe D by reason of the restricted opening a' in the nipple a causes a gradual diminishing of speed of said engine, until they are supplied with steam only through the restricted openings H in said valves. The operation of the damper mechanism is such that when the governor e causes the valve E³ to close, the steam flows from the pipe E' through the pipe e' to the cylinder A and causes the damper G' to open in proportion to the closing of the governor controlled valve E³.

Having thus fully illustrated and described suitable mechanism for embodying my invention I do not desire to be limited to the exact construction and arrangement of the parts thereof, herein shown and described, as many changes can be made therein without departing from the scope of my invention; therefore what I claim as new and desire to secure by Letters-Patent, is:—

1. A steam conductor leading from a suitable source of supply to an engine, a valve in said conductor, fluid controlled mechanism for actuating said valve, and mechanism controlled by the fluid pressure in said steam conductor adapted to relieve the pressure in the fluid controlled mechanism controlling said valve.

2. In a system for regulating mechanical

stokers, a steam conductor, a valve in said conductor to control the flow of steam therethrough, fluid controlled mechanism to actuate said valve, a fluid supply pipe leading from said steam conductor to said fluid controlled mechanism having a restricted passage therein through which the fluid passes to said mechanism, and means controlled by changes in pressure in said steam conductor to unload the pressure in said fluid supply pipe whereby said valve is instantly opened.

3. In an apparatus of the class described, a steam main, a steam conductor leading therefrom to the atmosphere, a valve therein, fluid controlled mechanism to actuate said valve, a pipe connected therewith and communicating with said steam main whereby said fluid controlled mechanism may be actuated to open and close said valve by reason of variations of pressure in said steam main, a nipple in said steam conductor having a restricted opening therein between said conductor and said valve, another steam conductor leading from said steam main to an engine, a valve in said steam conductor to control the flow of steam to said engine, fluid actuated mechanism to open and close said valve, and a fluid supply pipe leading from said mechanism and connected to said nipple at a point between said restricted opening therein and said first mentioned valve, whereby the fluid pressure in said fluid supply pipe will be relieved upon the opening of said first mentioned valve.

4. In an apparatus of the class described, a plurality of steam actuated motors, steam conductors for supplying steam thereto, regulating valves in said conductors, fluid actuated mechanism adapted to open and close each of said regulating valves, a fluid supply pipe leading from each of said fluid actuated mechanisms to a nipple having a restricted steam passage therein, a valve housing connected to said nipple and leading to the atmosphere, a valve therein adapted to open and close the passage therethrough, a fluid controlled mechanism to actuate said valve, a fluid supply pipe connected therewith communicating with said steam main, whereby, by reason of variations of pressure in said steam main, said last mentioned valves will be opened to relieve the fluid pressure in said fluid supply pipes and fluid controlled mechanisms connected therewith and permit the regulating valves operated thereby to be opened until the pressure in said steam main is increased sufficiently to cause the closing of said first mentioned valve, and fluid pressure in said fluid supply pipes is increased sufficiently to close said regulating valves.

5. In an apparatus of the class described, a regulating valve, pressure controlled mechanism adapted to actuate said valve, a steam conductor leading to said valve and

thence to a motor, to be actuated, a governor actuated valve in said conductor between said regulating valve and said motor, a damper operating mechanism, a steam supply pipe leading therefrom to a point in said conductor between said regulating valve and said governor actuated valve, and mecha-

nism controlled by variations of pressures in the source of steam supply to relieve the pressure in said pressure controlled mechanism and allow said regulating valve to open.

In testimony whereof I affix my signature.

THOMAS M. WILKINS.
